UNITED STATES PATENT OFFICE.

MALCOLM J. MCFARLANE, OF NEW ORLEANS, LOUISIANA.

FIRELESS COOKER AND HEATER.

Application filed June 7, 1924. Serial No. 718,639.

To all whom it may concern:

Be it known that I, MALCOLM J. MCFARLANE, a citizen of the United States, residing at New Orleans, in the parish of Orleans and State of Louisiana, have invented certain new and useful Improvements in Fireless Cookers and Heaters; and I do hereby declare the following to be a full, clear, and exact description of the invention, such as will enable others skilled in the art to which it appertains to make and use the same.

The present invention relates to improvements in fireless cookers and heaters, and has for an object to provide an improved device for use with either electricity or gas and adapted to be made in either single or multiple compartments.

It is another object of the invention to provide an inexpensive form of construction of fireless cooker and heater in which the heat will be more effectively retained against escape by radiation whereby to secure a greater economy in operation.

Further objects of the invention are to construct a device of this character in which the component materials will be cheap, wherein the manufacture may be conducted by simple methods and few operations and in which the resultant product will be compact, light and easily accessible to all interior parts.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a front elevation showing a duplex cooker and heater constructed according to the present invention.

Figure 2 is a fragmentary section taken vertically therethrough.

Figure 3 is a vertical section taken at substantially right angles to Figure 2.

Figure 4 is a cross section through one of the compartments, and

Figure 5 is a front elevation of the single device.

Referring more particularly to the drawings the device is contained in an outer casing 6 of metal, preferably a light relatively thin sheet metal which lends itself readily

to the cylindrical or other formation usually given devices of this kind. This casing 6 is provided with doors 7 and 8 hinged at one side as indicated at 9 and 10 and provided at the front edges with pivoted latches 11 adapted to engage with the keepers 12 upon the casing adjacent the door openings. The cylindrical casing is adapted to stand on end and the doors are made in the side walls thereof, the doors conforming to the general shape of the casing and being wide and substantially high, so as to give ready and convenient access to the interior chambers 13 and 14 for the purpose of placing and removing pots, kettles and other containers in which the food stuff or other material to be cooked is placed. One of these containers is shown at 15 in the lower compartment in Figure 3. The container is seated upon a stone 16 which is placed above the heating elements as later explained, the stone absorbing the heat given off by the heating elements and retaining this heat for a long time after the heating element has been turned off. This absorbed heat is radiated throughout the chamber or cooker and the heat is retained from radiation by the walls 17.

These walls are preferably of vitro-asbestos approximately one and one-half inches thick and constitute a lining within the metal casing 6. At the base of the casing is a bottom wall 18 also of non-conducting material which may be molded or otherwise formed in one piece with the side wall 17. The bottom wall 18 is provided with a central depression 19 adapted to receive the gas burner 20 lying beneath the upper surface of the wall 18 and provided with a mixture of gas and supporting oxygen from a pipe entering through the side wall of the casing 6 as indicated in Figure 4. This bottom wall 18 is also provided with a serpentine groove 22 for receiving a continuous electric resistance coil 23 looped about in the groove and extending beneath the upper surface of the bottom wall 18 and beneath a large surface area of the stone 16. The electrical connections are brought in at one side as indicated in Figures 3 and 4.

There is a division wall or partition 24 between the upper and lower compartments 13 and 14, this wall being also of appropriate non-conducting material and being preferably molded in one with the side wall 17.

which extends in common to both compartments and substantially the full height of the casing 6. The partition 24 is also formed with a central cavity or depression 25 to receive the gas burner 26 having its upper edge lying beneath the upper surface of the partition, and in this partition is also a similar serpentine groove 27 for receiving an electric resistance coil 28, the connections for which may join with the lead wires to a lower coil as indicated at 29, switch buttons 30 and 31 being placed in the branch lines and a master switch 32 being placed in the main line. The arrangement 10 permits the energizing of either upper or lower coil individually.

The same arrangement is possible for the gas burners, the main supply pipe to which is indicated at 33 in Figure 1, the two burners being supplied independently by the branch pipes 34 and 35 each having valves 36 and 37 therein for independent operation.

In manufacturing the device, the casing 25 6 is made independently of course from the liner and this liner is built up by molding or otherwise in a composite whole including the top wall 38. The top wall 39 of the outer casing 6 is, however, not originally attached 30 to the casing, the casing being open from above so that the liner may be slid down therein.

After the lining is in place, the cover 39 is put on and secured as by brazing or spot-welding, the joint being afterwards suitably finished or smoothed so as to give the appearance of continuity.

Of course the door openings are originally left in the liner and the flanges 40 about the door openings are not originally pressed in. This operation is conducted after the liner is in place and the flanges 40 are preferably on an incline as shown in Figure 3. Such flanges serve to sustain the liner at appropriate points and the flanges 45 above and below the partition 24 materially assist to reinforce and strengthen the construction at this point, but the material itself possesses substantial body and strength 50 and in devices that have already been built it is found that no additional reinforcement is necessary.

The doors 7 and 8 are also provided with flanges 41 complementary to the flanges 40 and inclined mutually thereto, so that the doors may close with a tight fit. The dissipation of heat through the flanges 40 and 41 is found to be negligible.

In Figure 5 there is shown a single heater 60 containing only one chamber but the parts are identical in this case with for instance the lower compartment of the double construction already described and except that there is no partition and associated parts, 65 this device is in all respects similar in con-

struction, function and operation to the double form of the invention already referred to.

In the use of the device either the gas burner is lighted or the electric coil energized and the containers 15 directly heated by placing them upon the bottom wall 18 of the partition 24 or by placing these containers upon the stone 16. The stone becomes highly heated and absorbs great 75 quantity of heat which it afterwards continues to give off for a long period of time after which the gas burner is extinguished and the electric heating coil deenergized.

It is at times desirable to energize the 80 coil and also light the burner. The direct application of the flame from the gas burner to the stone enables the latter to acquire a high heat and this application centrally 85 of the stone enables the heat to be absorbed substantially equally in all directions. The heat from the electric coil is of a milder form yet extending simultaneously to all parts of the stone which would be impracticable from a standpoint of economy 90 in construction and operation of the gas burner. However, the heat is acquired by the outer edges of the stone possibly more quickly by the use of the resistance coil in the position stated and a high heat is rapidly 95 absorbed by the stone with the use of both heated elements so that the economy in the one form of heating enables a saving from a more prolonged application of heat from the other heating medium. Either upper or lower compartment may be put in 100 operation independently of the other.

It is obvious that various changes and modifications may be made in the details of construction and design of the above specifically described embodiment of this invention without departing from the spirit thereof, such changes and modifications being restricted only by the scope of the following claims.

What is claimed is:—

1. A fireless cooker and heater comprising a thin metallic casing, a liner fitting in the casing and including integral side, top and bottom walls, said bottom wall having in its upper side a centrally disposed cavity and a serpentine groove thereabout, both said cavity and groove opening through the upper side of the bottom wall, a gas burner seated in the cavity, means housed in the liner and extending in the casing for supplying fuel to the gas burner, and an electric resistance coil seated in said groove and connected through the liner and casing to an external source of energy.

2. A fireless cooker and heater comprising a thin metallic casing having separate upper and lower door openings in its sides, doors for closing said openings, a composite insulating liner fitting in said casing and hav-

ing integral top, bottom and an intermediate partition walls providing upper and lower compartments, said partition and bottom walls each having a central cavity and a serpentine groove opening respectively through the upper faces of the partition and bottom walls, a gas burner in each cavity, a connection from an external source of

fuel to said burners, an electric resistance coil in each serpentine groove, and an external connection from a source of electric energy to said coils, whereby said compartments may be independently and simultaneously used as fireless cookers and heaters. 10
